NONGLARE HEADLIGHT LENS

George E. Smith, Long Branch, N. J.

Application January 10, 1934, Serial No. 708,115

1 Claim. (Cl. 240—41.4)

The present invention relates to certain new and useful improvements in lenses and consists in the provision of an improved lens for headlights.

5 An object of the invention is to provide a lens especially adapted for use with the headlights of motor driven vehicles which will effectively prevent glare.

The invention together with its objects and 10 advantages will be best understood from a study of the following description taken in connection with the accompanying drawing wherein:

Figure 1 is a plan view of the lens with certain parts broken away and shown in section, 15 and

Figures 2 and 3 are detail sectional views taken substantially on the lines 2—2 and 3—3 respectively of Figure 1.

Referring to the drawing by reference numerals it will be seen that my improved headlight lens comprises a disk like body 5 that in 20 its center is provided with an integral circular hollow portion or chamber 6 the walls 7 of which project beyond the plane of the disk 5 and are 25 convexed on their outer surfaces and concaved on their inner surfaces. The chamber 6 is adapted to contain a suitable fluid and on the rear side of the lens the part 7 thereof is integral with a narrow elongated radial extension 8 forming 30 with the adjacent part of the lens 5 a filling neck or passage 9 through which the fluid is introduced into the chamber 6. A plug or the like 10 seals the neck 9 as clearly shown in Figures 1 and 3.

35

In actual practice it has been found that in providing a lens in accordance with the present invention, with a centrally located circular chamber having a liquid wholly or partially filling the same, glare from the headlight will be greatly diminished if not totally eliminated.

It will be further apparent that a lens of this character may be economically and cheaply made and can be used with headlights of general construction without any material alteration in the construction of the head lamp casting.

Having thus described my invention, what I claim as new is:

A head lamp lens having a hollow central portion defining a fluid chamber opposing walls of which project beyond the plane of the lens and have convexed outer surfaces and concaved inner surfaces, and a narrow channel-shaped part formed on the inner face of the lens with its 75 lower end formed with the upper portion of the inner wall of the chamber and its upper end terminating short of the upper portion of the lens, the channel of said member, with a portion of the rear face of the lens, forming a passage, the lower end of which communicates with the chamber and the upper end of which opens out through the upper end of the channel member, and a stopper for closing the upper end of said passage.
